SASH BALANCE

Owen L. Dautrick, Detroit, Mich.

Application August 5, 1938, Serial No. 223,173

9 Claims. (Cl. 16—198)

The present invention relates in general to means for balancing window sashes and other analogous articles which require to be raised and lowered, and is more particularly concerned with improvements in devices for such purpose of the type wherein the weight of the article is balanced by the action of one or more springs. The present application constitutes a continuation-in-part of my copending application, Serial No. 10 184,515, filed Jan. 12, 1938.

It is a primary object of the present invention to provide an improved sash balance of the spring type which may be used with standard window frames.

15 A further object is to provide novel closing means for concealing a sash balance mechanism of the herein described type, which effectively conceals the device yet enables ready and easy access thereto when necessary.

20 Another object is to provide in a device of the character described, improved means for connecting the balancing springs with the associated instrumentalities, whereby improved spring action and operation may be secured.

25 Still another object is to provide improved means for adjusting the spring tension to accommodate the mechanism for window sashes of different weights.

It is also an object of the herein described invention to provide an improved sash balance which incorporated novel bracket supporting means arranged to additionally form a support for a mechanism concealing plate, and in which this plate may constitute the sub-head jamb of 35 the window frame, thus enabling my improved balance mechanism to be utilized with a standard window frame structure.

Although for purposes of illustration the invention is disclosed as being utilized with window sashes, it will be apparent to those skilled in the art that the invention may with equal facility be utilized with other types of closure panels, such as doors, sliding panels, etc., without departing from the principles of the invention.

45 Other objects and features of the invention will more fully appear from the following detailed description, taken in connection with the accompanying drawings which illustrate several embodiments thereof, and in which:

50 Figure 1 is a plan view of a sash balance embodying the features of the present invention, the sash balance being applied to a window frame of standard construction;

Figure 2 is an elevational view of the same;

55 Figure 3 is an enlarged vertical fragmentary

section through the same, taken substantially on line III—III of Figure 1;

Figure 4 is a similar view taken substantially on line IV—IV of Figure 1.

Figure 5 is an enlarged fragmentary detail view 5 partly in section showing the manner in which the tensioning spring is secured to the spring rod and winding drum;

Figure 6 is a transverse sectional view taken through the spring and associated rod, showing 10 the manner in which the associated end of the spring is slidably connected to the rod, taken substantially on line VI—VI of Figure 5;

Figure 7 is a similar sectional view taken 15 through the rod adjacent the other end of the spring, taken substantially on line VII—VII of Figure 5;

Figure 8 is an enlarged fragmentary view partly 20 in section, showing the manner in which the tensioning pulley is removably connected to the spring rod;

Figure 9 is a transverse sectional view through 25 the same, taken substantially on line IX—IX of Figure 8;

Figure 10 is a detail view looking at the outer 30 end of one of the winding drums, showing the manner in which the flexible sash tape is secured to the drum, taken substantially on line X—X of Figure 5;

Figure 11 is a view similar to Figure 1 of a 35 slightly modified construction of sash balance embodying the features of the present invention;

Figure 12 is a view similar to Figure 2, showing the modified structure in elevation;

Figure 13 is an enlarged transverse sectional 40 view of the same, taken substantially on line XIII—XIII of Figure 11;

Figure 14 is an enlarged fragmentary trans- 45 verse sectional view taken substantially on line XIV—XIV of Figure 11; and

Figure 15 is an enlarged fragmentary trans- 50 verse sectional view of the same, taken substantially on line XV—XV of Figure 11.

As shown on the drawings:

The invention is disclosed as being applied to 45 a standard window frame or casing which as usually constructed contains spaced side jambs 16 and 17 which are connected at the top of the frame by a head jamb 18 in any suitable manner. Window sashes (not shown) are mounted in this frame for raising and lowering movements, and the present invention is primarily concerned with improved means for balancing the weight of these sashes so that they may be easily actuated. 55

As generally shown in Figures 1 and 2, the 55

preferred form of the invention embodies individual spring units which are independent in operation and which may be individually adjusted to vary their initial spring tension.

- 5 Such an arrangement has been found to be highly desirable from an installation standpoint, since by using units of standard construction, the complete balancing mechanism for any window, may be varied to meet different installation requirements. For example, in cases where the sashes are relatively small or where the most economical installation is required, a single balancing unit connected to one side only of each sash may be furnished. On the other hand, 10 where the sashes are larger and heavier or where the matter of economy is not a limiting factor, two units may be furnished for each sash, these units being independently connected to both sides of the sash.
- 15 20 I have shown the balancing mechanism for a window containing two sashes, two spring units being provided for each sash. The spring units are arranged in right and left-hand pairs, the two units for connection to the left side of the two sashes being mounted together and the two units for the right sides of the two sashes being mounted together. The units are arranged to be mounted at the upper corners of a standard window frame.
- 25 30 Each spring unit comprises an elongate rod 19 which may be constructed of any suitable material, wood having been found satisfactory for this purpose. As shown in Figure 5, one end of this rod is centrally apertured to receive a trunnion pin 20 which is driven into the end of the rod and projects outwardly therefrom to form a pivot for this end of the rod and also serve as a support for rotatably supporting a winding drum 21 which may be constructed of any suitable material such as wood.
- 35 40 The winding drum 21 is provided at its innermost end with a cup-shaped metal cap 22, the bottom surface of this cap abutting the end of the rod to form a bearing surface. The bottom 45 of this cap at its periphery is provided with a circumferential bead 23 which has a cutout portion 24, as shown in Figure 3, for a purpose which will be explained later.

45 50 This end of the rod 19 is rotatably supported in an end bracket 25, and the other end of the rod is rotatably supported in a bracket 26. Each of these brackets is arranged to support two of the spring units.

55 60 The bracket 25 embodies a substantially rectangular main plate portion 27 which is secured in surface engagement with the associated side jamb. This portion of the bracket is apertured to receive the projecting ends of the trunnion pins, the jambs being provided with suitable sockets 28 so as to enable the ends of the trunnion pins to project through the plate portion 27.

65 70 The bracket 26, as shown in Figures 1 and 2, is of substantially U-shaped construction and has spaced leg portions 29 and 30 with aligned apertures of sufficient size to permit the associated end of the rod 19 to project therethrough. This bracket may be secured with the spaced ends of the U-shaped legs against the head jamb 18 as by a centrally disposed screw 31 extending 75 through the bridging portion connecting the legs.

75 The rod 19 is retained against longitudinal removal from the brackets 25 and 26 by means of a diametrically extending pin 32 which has its end projecting beyond the surface of the rod.

This pin is positioned between the legs 29 and 30 of the bracket 26 and bears against the inner surface of leg 30, thus holding the rod against movement in such direction as would tend to cause the end of the trunnion pin to be withdrawn from its support in the plate 27 of bracket 25.

Surrounding the rod 19 is a coiled tension spring 33 which is secured at one end to the cap 22 associated with the winding drum 21. This end of the spring is anchored by carrying the marginal end of the spring through the cutout portion 24, thence through the passageway cooperatively formed by the bead and the associated end of the winding drum. The extreme 15 end of the spring is then again brought out through the cutout portion and deflected as shown at 34 in Figure 3.

The opposite end of the spring is secured to a sleeve member 35 of generally tubular construction. This member is provided with an inwardly struck rib portion 36 which extends longitudinally of the sleeve and is adapted to slidably extend into a slot 37 which extends longitudinally of the rod 19 and is formed in the surface 20 thereof. The innermost end of this sleeve member is deflected to form a circumferentially extending bead 38 having a cutout portion 39 which forms an entrance opening to the interior of the bead. The associated end of the spring is 25 secured in a similar manner to that in which the other end is secured to the cap 22. That is, the marginal end of the spring is carried through the cutout portion 39, thence through the interior of the bead 38. The extreme end portion of the spring is then brought out through the cutout portion 39 and deflected as shown at 40 in Figure 6.

With the construction just described, it will be apparent that the sleeve 35 anchors the associated end of the spring to the rod 19 in such manner that this end of the spring will be rotated with the rod but is free to move longitudinally of the rod when the spring tension is increased or decreased.

The utilization of a bead for engaging at least one of the end turns of the spring in the anchoring means has been found to possess desirable advantages over arrangements wherein the extreme tip end of the spring is simply deflected 50 to form a single point hook connection.

In my improved arrangement, the beaded portion engages the last turn of the spring substantially throughout its circumference, thus holding the coil erect and opposing any tendency of this coil to tilt. By holding the end coils erect in this manner, the intermediate coils will also have a tendency to remain erect during increases and decreases of the spring tension. Moreover, the bead allows for changes in 60 diameter of the spring coils during changing of its tension.

As a result, a much more favorable spring action is secured by eliminating excessive strain and reducing friction at the points of anchorage.

65 Also, I have found that my improved anchor means enables lighter spring wire to be used in which the torsional forces are relatively lower than in the case of heavier spring wire. A much improved and truer counterbalancing results, 70 and the recoil action of the spring is lessened.

Each winding drum 21 is arranged to have a flexible tape 41 wound and unwound thereon. One end of this tape is connected to a sash in any suitable manner, and the other end is con-

nected to the winding drum. This latter connection may be accomplished in the manner shown in Figure 10. The drum is provided with an inwardly extending key slot 42 and the end of the tape to be secured to the drum is provided with a transversely extending enlarged end 43 which may be inserted endwise into the slot and retain the end of the tape against removal therefrom, but permitting the tape to be wound around the drum.

Each spring unit is arranged to have its spring initially tensioned to any predetermined or desirable amount. This is accomplished by rotating the shaft 19, and a suitable latch for retaining the shaft against rotation in one direction is provided. For this purpose, a latching plate 44 is pivoted at one edge by means of trunnions 45 and 46 in the legs 29 and 30 of bracket 26 for swinging movement. The free end of this plate is arranged to ride on the surface of the rod 19, as shown in Figure 4, in the path of movement of the projecting ends of pin 32. Thus, the shaft 19 may be rotated in one direction, but when it tends to move in the reverse direction, one end or the other of the pin 32 will engage against the free edge of the plate 44 and thus be latched against movement. The plate 44 is normally moved to latching position by the action of gravity.

In order to facilitate rotation of rod 19 for tensioning its associated spring, each rod is provided at its innermost end with a diametrically extending end slot 47. A winding pulley or sleeve 48 is arranged to be removably placed over the slotted end of the rod, this pulley having an internal web 49 which will enter the slot 47 and anchor the pulley for rotative movement with the shaft. The outer surface of the pulley is arranged to have a pull cord 50 wound thereon by means of which the shaft may be rotated simply by pulling on the cord.

It will be noted that the slotted ends of all the winding units are adjacently disposed and that the winding pulley may be selectively connected with any one of the rods 19 of the spring units for initially tensioning their springs to the desired amount.

By utilizing a splined connection between the inner end of the spring and rod, the torsional effect only of the spring is utilized. Moreover, such a connection prevents the spring coils from overlapping and locking with each other when tensioned, and the spring coils will at all times lie smoothly and regularly along the rod. This arrangement also permits the use of different lengths of springs without having to modify the other parts of the mechanism.

In the preferred form of my invention, the brackets 25, which are utilized for supporting the spring units on the side jambs of the window frame, are also utilized to support closure and concealing members for concealing the sash balance mechanism position at the upper end of the window frame.

The front side of the sash balance mechanism is concealed by means including a removable plate 51, as shown in Figure 1, which is secured as by screws 52 and 52' to abutment flanges 53 and 53' respectively formed on the supporting brackets 25-25' associated with the side jambs of the window frame.

Each of these end brackets at its lowermost edge is provided with spaced apart inverted L-shaped portions 54 and 55, as shown in Figures 2 and 3. These portions are spaced from the plate

27 and are arranged to receive the ends of a closure plate 56 therein.

The associated end of the plate 56 may be removably secured to the portions 54 and 55 as by suitable screws 57 and 58. The opposite end 5 of plate 56 is similarly secured to the bracket 25'. With this arrangement, the plate 56, in effect, forms a sub-head jamb for the sashes and may have secured thereto a parting strip as shown at 59.

It will be observed that the ends of the plate 56 are inwardly disposed at the plate 27 of the bracket 25, so that the flexible tape 41 does not have to pass through the plate 56. The portions 54 and 55 have their adjacent edges spaced apart to form a slot 60 for one of the tapes, and the portion 54 has its forward edge spaced from the flange 53 to form a slot or opening 61 to permit passage of the other tape.

If desired, the rear edge of plate 56 may be provided with a longitudinally extending tongue 62 adapted to fit into a suitable groove 63 formed in a back plate member 64 at the rear side and top of the window frame. This tongue may have its upper edge rounded to facilitate swinging movement of the plate 56 when it is removed and inserted into closing position. Also, the forward edge of this plate is beveled as shown at 65 so that it will not bind against the plate 51 when swung into and out of closing position.

The modified sash balance construction as shown in Figures 11 to 15 inclusive, operate upon the same general principles as the preferred form of the invention, but differs therefrom in the construction of certain of its parts. The modified construction, as disclosed on the drawings, may be constructed either as a single or double unit, and it is thought that a description of the double unit will be sufficient to clearly show the detailed differences between the preferred and modified constructions of the invention.

The double unit comprises an elongate rod 66 which is provided at its ends with trunnion pins 67-67 projecting outwardly from the ends of the rod to form pivots for winding drums 68-68 of 45 suitable material such as wood.

The trunnions 67 are of sufficient length to project past the winding drums and support the rod 66 for rotation in end brackets 69 and 70 which are secured as by screws 71 in surface engagement with the respective side jambs 16 and 17 of the window frame.

Each bracket is provided with a centrally cut-out portion 72 which admits of the associated trunnion pin being seated behind a hooked projection 73 by carrying it through an entrance opening 74. In its supported position in an associated end bracket, the trunnion pin projects outwardly past the bracket into a dado or groove 75 at the upper end of the associated jamb.

For additionally supporting the rod 66 intermediate its ends, an intermediate bracket 76 is provided, which may be secured to the fixed head jamb by means of a suitable screw 77.

The rod 66 extends through a suitable aperture 78 in the bracket, as shown in Figure 14. The rod is rotatably supported in the bracket in an open ended sleeve 79 which partially surrounds the rod and has one end thereof outwardly deflected to form a radially extending end 70 flange 80. The other end of the sleeve is inwardly deflected to form a radially extending end flange 81, Figure 14. This flange is adapted to fit into a groove 82 extending longitudinally of the rod in its surface. This sleeve may be sup- 75

ported against edgewise movement in the bracket in any suitable manner.

Pivottally disposed on opposite sides of the intermediate bracket, tension springs 83 and 84 are 5 coiled around the rod. One of these springs will be a right-hand spring and the other a left-hand spring. The springs are similarly connected at their ends with the winding drums and the rod 66.

For example, the outermost end of spring 84 is 10 anchored to a sleeve 85 which surrounds the innermost end of the winding drum and is secured thereto as by an anchor pin or other suitable means (not shown). Thus the sleeve and drum have unitary movement. Any appropriate means 15 may be utilized for securing the associated spring end to the drum, but one satisfactory method is to provide the sleeve 85 with a projection 86 over which the spring end may be hooked. If desired, this projection may be bent around the spring 20 to hold it against the end of the winding drum.

The other end of the spring is secured to a sleeve 87 which surrounds the rod 66. This sleeve is retained against rotational movement relative to the rod by means of an internal rib which 25 is adapted to extend into the groove 82 for sliding movement therein. It will thus be evident that the sleeve as thus secured will be rotatable with the rod, but is free to move longitudinally on the rod when the associated spring has its 30 tension increased or decreased.

As in the preferred form of the invention, the winding drums 68 are in this case adapted to have the flexible tape 41 wound thereon.

For simultaneously tensioning the springs 83 35 and 84 to the same amount, a tensioning pulley 88 is loosely mounted on the rod 66 for rotative movement thereon. This pulley has a winding surface adapted to have a winding or pull cord wound thereon in the same manner as the wind- 40 ing pulley in the preferred form of the invention.

One end of the pulley is provided with clutching teeth 89 which are adapted, when the pulley is slid along the rod into abutting relation with the sleeve 79, to clutchingly engage the flange 45 80. Upon rotation of the pulley 88 by pulling upon the tensioning cord, the rod 66 will be rotated in the proper direction to tension the springs 83 and 84. These springs may be tensioned to just the right amount to counter-balance 50 the weight of the sash which is connected thereto through the tapes 41. Rotation of the rod in the opposite direction, which will tend to release the tension on the springs, is prevented by means of a suitable latching arrangement.

55 This latching arrangement comprises a pawl 90, as shown in Figure 14, which is swingably mounted on a pivot 91 secured to the intermediate bracket 76. This pawl is held in latching position by gravity. Should it be desirable at any time 60 to lessen the tension on the springs, this may be easily accomplished by actuating the tensioning pulley in a tensioning direction sufficiently to enable the pawl to be manually released, whereupon by releasing the pressure or pull on 65 the tensioning cord, the springs will be permitted to unwind and rotate the shaft until the proper tension remains in the spring. The pawl may then be released to latch the rod against further unwinding movement.

70 A single spring unit, as shown in Figure 11, may also be constructed after the manner of my modified construction. This unit operates on the same principles as the double arrangement except that instead of providing two springs 75 and two winding drums only one spring and one

winding drum is necessary. In the single arrangement, instead of having connecting tapes secured at opposite sides of the sash, a single tape is secured at one side of the sash as in my first arrangement. It will also be noted that 5 in the case of the single arrangement, the tensioning pulley may be removed from the rod, when it is not being used, the same as in my preferred construction.

Since it is necessary in spring balanced mechanisms for sashes, where the load is constant and the power supplied by the spring is variable, to provide some means to balance the sash at all points of its position of adjustment, it is understood that weatherstripping may be provided for 15 this purpose, as described in my aforementioned co-pending application.

From the foregoing description, it will be apparent that the present invention provides an improved sash balance mechanism of the spring type which may be utilized with standard window frames; which embodies novel closing means for the balance mechanism, which is supported from the bracket utilized for supporting the balance mechanism, whereby the mechanism is effectively concealed and yet is so arranged that access to the mechanism may be readily and easily accomplished, when necessary; improved means for connecting the balancing springs with the associated parts of the mechanism, whereby novel and improved spring action may be secured; and which includes improved means for adjusting the spring tension to accommodate the balance mechanism for window sashes of different weights.

It is, of course, to be understood that although I have described in detail a preferred and modified embodiment of my invention, the invention is not to be thus limited but only insofar as defined by the scope and spirit of the appended claims.

I claim as my invention:

1. A sash balance mechanism comprising a rod supported for rotative movement, a winding drum rotatably supported at one end of said rod and adapted to have a flexible member connectible 45 to a sash wound and unwound thereon, an elongate coiled spring surrounding said rod and extending away from said drum, one end of said spring being connected to said drum, and the other end of said spring being connected to said 50 rod for rotative movement therewith, means adjacent the latter connection of the spring for manually rotating said rod in one direction to tension said spring, means for latching said rod against rotation in the opposite direction, said 55 latter means including a projection carried by said rod, and a hinged plate having its free end normally riding on said rod in the path of travel of said projection.

2. In a sash balance, a drum supported for 60 rotative movement, said drum having a winding surface, a cap member disposed over one end of said drum, a circumferentially extending bead formed in said cap, said bead being open toward the associated end of the drum and cooperating 65 therewith to form a circular passageway, a cut-out portion in said bead defining an entrance to said passageway, and a coiled spring having one of its end margins extending through said opening and passageway.

3. In a sash balance, a rotatably mounted rod having a longitudinally extending surface slot, a sleeve member surrounding said rod, said sleeve having an inwardly deflected portion disposed in said slot, a circumferentially extending tubular 75

bead at one end of said sleeve having a cutout portion defining an entrance opening to the interior of said bead, a coiled spring surrounding said rod, said spring having one of its end margins extending through said opening and looped within said bead.

4. In a sash balance, a normally stationary rotatable rod, a rotatable winding drum at one end of said rod adapted for connection to a sash, 10 a spring interconnecting said rod and drum, said rod having an end slot at its other end, a tubular second winding drum removably slidable over said latter end, said second drum having an internal web arranged to enter said slot, and a 15 flexible pull member adapted to be wound on said latter drum.

5. In a sash balance, a rotatably mounted elongate member, a first winding drum resiliently connected to said member and arranged for connection with a sash, a tubular second winding drum removably slidable over an end of said member, means removably connecting said second drum and member, and a flexible pull member adapted to be wound on said second drum.

25 6. In a sash balance mechanism, an elongate coiled spring, a rotatably mounted member, and means for connecting one end of said spring to said member, said means including an element engageable with at least one end turn of the spring at a plurality of points in its circumference, whereby the turns of the spring are retained erect during increase and decrease of the tension of said spring.

30 7. In a sash balance mechanism, an elongate coiled spring, a rotatably mounted member, a

normally non-rotative member, means for anchoring one end of the spring to the rotatable member, and means for anchoring the other end of the spring to the normally non-rotative member, said means in each case having parts arranged to engage at least one end turn of the spring and hold it against tilting during increase and decrease of the tension of the spring.

8. In a sash balance mechanism, an elongate coiled spring, a rotatably mounted member, a 10 normally non-rotative member, first means for anchoring one end of the spring to the rotatable member, second means for anchoring the other end of the spring to the normally non-rotative member, said first means and second means in 15 each case having parts arranged to engage at least one end turn of the spring and hold it against tilting during increase and decrease of the tension of said spring, and a connection enabling movement of one of said means in a direction axially of said spring.

9. In a sash balance, an elongate rotatably mounted rod, an elongate coiled spring surrounding said rod and having one end anchored to the rod, a pair of winding drums respectively at the 25 ends of said rod, one of said drums being rotatable relatively to said rod and connected with the other end of said spring, said one of said drums being arranged for connection with a sash, means for removably connecting the other of 30 said drums to the rod, and a pull cord for rotating the latter drum to vary the tension of said spring in its relation to said one of said drums.

OWEN L. DAUTRICK. 35
